(57) **CLAIM**

The ornamental design for a stadium bag, as shown.

DESCRIPTION

FIG. 1 is a right front perspective view of the stadium bag according to a first embodiment of the invention; FIG. 2 is a left front perspective view of the stadium bag according to the first embodiment of the invention; FIG. 3 is a front elevation view of the stadium bag according to the first embodiment of the invention; FIG. 4 is a rear elevation view of the stadium bag according to the first embodiment of the invention; FIG. 5 is a left side elevation view of the stadium bag according to the first embodiment of the invention; FIG. 6 is a right side elevation view of the stadium bag according to the first embodiment of the invention; FIG. 7 is a top plan view of the stadium bag according to the first embodiment of the invention; FIG. 8 is a bottom plan view of the stadium bag according to the first embodiment of the invention; and, FIG. 9 is a left front perspective view of the stadium bag according to a second embodiment of the invention. FIGS. 1-9 show the new design for the stadium bag in solid lines with broken lines showing environmental association matter for illustrative purposes only and forming no part of the claimed design. The broken lines in the drawings illustrating a bench and cushion represent environment. The remaining broken lines illustrate portions of the stadium bag. None of the broken lines form part of the claimed design. The stadium bag is shown with a symbolic break in the straps. The appearance of any portion of the article between the break lines forms no part of the claimed design.
